SCOURING AND LIKE ROLL

John Hugh Franklin, Rushden, England, assignor
to Fred Hawkes (N. V. Engineers) Limited,
Rushden, England, a British company

Application May 6, 1948, Serial No. 25,491
In Great Britain May 21, 1947

6 Claims. (Cl. 51—194)

1

This invention relates to rolls of the kind adapted to be secured upon the rotary shafts of appropriate machines and to be fitted, peripherally, with bands of abrasive material such as sand paper or fine emery cloth, felt or other suitable fibrous material, wire tease, and so on, for the performance of scouring, polishing, buffing and analogous finishing operations upon a variety of classes of work.

In this connection the invention is intended for application primarily to heel and sole scouring rolls such as are commonly used in the finishing stages of the manufacture of boots and shoes.

The invention, moreover, has reference particularly to rolls of the type comprising two parts which are hinged together for relative movement and have associated therewith releasable latch means for locking them together in the closed position for use. The said two parts are formed with complementary rim portions which, upon the parts being brought and latched together, provide a continuous circular rim adapted for the support of a band of scouring or like material. Release of the latch means permits of the opposed ends of the two parts being swung away from each other to effect opening of the roll for the purpose of facilitating removal of one band and its replacement by another. For instance, it may be desired to replace a worn band by a fresh one, or to change a band for another of a different quality or character. In any event, in a roll of the type referred to, the aforesaid opposed ends of the two hinged parts are furnished with means for attaching thereto the ends of a band, and closure of the roll results in a band so attached being tightened about the rim. Moreover, the latch mechanism usually comprises a pair of opposed slidably engageable latch members which are carried by the respective hinged parts and formed with complementary angular teeth, one of the latch members being movably mounted upon one of the roll parts for movement under spring control relatively to the opposed member fixed in the other part. As heretofore constructed the movable latch member has customarily been formed with lateral extensions adapted to function as thumb or finger pieces whereby release of the latch could be readily effected.

In practice, however, rolls of the particular type just described tend to be dangerous in use and, in fact, no longer satisfy the existing stringent safety regulations. Thus, for instance, when used for scouring, say, the heels of boots or shoes, there is a possibility that a boot or shoe will slip and as a consequence strike the laterally projecting thumb or finger pieces thereby permitting the roll to fly open with the attendant risk of injury to the operator's hands and/or to nearby parts, such as the dust extractor hood, of the machine. With a view to minimising such

2

risks attempts have heretofore been made to enclose the sides of the roll by means of cover plates, but in this case it was necessary to operate the thumb or finger pieces by means of a rod or other tool inserted through an opening in the appropriate cover plate. This, naturally, proved to be a troublesome operation.

The object of the present invention is the obviation of the foregoing difficulties by the provision, in a roll of the type herein referred to, of an improved latch operating mechanism designed to permit of total enclosure of the sides of the roll, without dangerous projections, as will be hereinafter described.

According to this invention, instead of the movable latch member being directly depressible by the operator's thumbs or fingers, as heretofore, it is adapted to be acted upon and withdrawn, to effect release of the hinged part of the roll, by means of a latch actuating member operable at one side of the roll.

In a convenient embodiment of the invention, one of the latch members is mounted for movement slidably and is directly engaged with a part of or on a pivoted latch actuating member which is operable by a push button disposed at one side of the roll.

The idea is to provide a latch actuating member which can be readily moved manually, through an opening in a side cover, and yet remain entirely within the confines of the said cover—that is to say, without lateral projection of the actuating member at any time from the smooth outer surface of the cover. As will be appreciated, moreover, whatever the construction adopted, appropriate movement of the actuating member is translated into the desired movement of the movable latch member, to release the latter from engagement with the tooth or teeth of the opposed latch member.

A specific constructional example of the invention applied to a heel scouring roll will now be described with reference to the accompanying drawings, wherein

Figure 1 is a side view of the roll as it appears when closed and with the side cover plate removed.

Figure 2 is an end view of the roll with one of the two hinged parts thereof removed and with the removable side cover plate broken away on the line II—II of Figure 1 to disclose the push button lever and the slidable latch member.

Figure 3 is a general perspective view of the roll, shown unlatched and open.

Figure 4 is a perspective view of the side cover plate and of the screws whereby it is secured in position, and

Figure 5 is a perspective view of a band of felt which is fitted peripherally to the roll for the support of strip abrasive cloth or paper.

Like parts are designated by similar reference characters throughout the drawings.

Referring to the drawings it will be seen that the improved heel scouring roll comprises a main body part 1 and a complementary part 2 which two parts are hinged together at 3. The part 1 has a substantially semi-circular rim portion 4 and a hub 5 which are connected by an intervening integral web 6 constituting a side cover for the roll. The hub 5 extends wholly from the inner face of the side cover 6. The hinged part 2 is also formed with a substantially semi-circular rim portion 7 adapted to complement the rim portion 4 of the part 1 and thereby provide a virtually continuous circular rim upon the parts being closed and latched together as shown in Figure 1. As in a heel scouring roll of conventional construction, the appropriate end of the rim portion 4 is bifurcated at 8 to receive an interfitting lug 9 formed on the opposing end of the rim portion 7, the spaced limbs of the bifurcation and also the lug being drilled to receive a hinge pin 10 riveted over at its ends. Moreover, the opposite ends of the rim portions 4 and 7 are provided, in accordance with normal practice, with spikes 11 and 12 arranged to engage in holes or recesses 13 and 14 respectively upon closure of the roll. The opposite ends of the strip abrasive cloth or paper (not shown) are impaled upon and retained by the said spikes.

The outer side of the hub 5 is formed integrally with a laterally extending lug or ear 15 which is longitudinally bored at 16, tangentially with respect to the hub, to receive a slidable latch member 17. The bore 16 is closed at its inner end. The latch member 17 is fashioned from a short length of steel rod of circular cross-section and at its outer, i. e. operative, end is formed with a protruding single tooth 18. To maintain it in its correct position angularly within the bore 16, the slidable latch member 17 is provided with a lateral pin 19 arranged, as shown in Figures 2 and 3, to work in a guide slot 20 formed in the lug or ear 15. The inner end of the latch member 17 is axially recessed to accommodate one end of a compression spring 21 the opposite end of which is arranged to bear on the opposing closed end of the bore 16. The spring 21 therefore normally urges the tooth 18 into its fully projected position shown in Figures 1, 2 and 3, and depression of the latch member 17 takes place against the spring action. For co-operation with the toothed latch member 17 there is provided a complementary toothed latch member 22 which is fixed, e. g. by rivets 23, to the hinged part 2. The said member 22 is made of hardened metal and is formed with circumferentially spaced front and rear catch teeth 24 and 25 respectively. Thus, when closing the roll by movement of the hinged part 2 towards the main body part 1, the front catch tooth 24 will first snap into engagement with the tooth 18 to hold the roll partially closed, such engagement being permitted by relative movement of the slidable latch member 17 first inwardly against, and then outwardly under, the action of the spring 21, whereupon the rear catch tooth 25 will similarly snap into engagement with the tooth 18 securely to lock the part 2 in its fully closed position. In short, the closure of the roll is effected in two stages, this being advantageous in so far as it enables the operator, at the termination of the first stage, to pause and, with the roll held partly open, finally check the fitting and alignment of the strip abrasive cloth 75

or paper, before completing the closure as aforesaid.

To enable the slidable latch member 17 to be forcibly depressed manually to effect release of the hinged part 2 and in turn permit the roll to be opened, as occasion demands, there is provided, in accordance with the characteristic feature of this invention, a bell crank lever 26 which is fulcrumed upon a screw 27 screwed into a laterally protuberant boss 28 on the hub 5. The lever 26 is disposed in a plane at right angles to the side cover 6. The inner arm 29 of the said bell crank lever 26 is furnished with a cylindrical stud 30 (or a roller) which projects inwardly from the side of the lever through a slot 31 formed in the wall of the longitudinally bored lug or ear 15 and thence into a transverse recess 32 cut in the adjacent side of the slidable latch member 17. The arm 29 is movable up and down with a recess 33 formed in the side of the lug or ear 15. The outer arm 34 of the bell crank lever 26 is formed integrally with a push button 35 arranged to be located in a circular hole 36 (see Figures 2 and 4) formed in a side cover plate 37. The plate 37 is centrally dished and is removably secured to the outer end of the hub 5 by means of screws 38 (Figure 4). The push button 35 lies practically flush with the outer face of the side cover plate 37. By subjecting the push button to lateral pressure, inwardly, by the thumb or finger, the inner arm 29 of the bell crank lever is caused to press, through the medium of the stud 30, upon the slidable latch member 17 which latter as a consequence is withdrawn from engagement with the latch member 22 against the action of the compression spring 21. Conversely, upon release of the push button 35, the slidable latch member 17 will automatically resume its projected position under the reaction 40 of the compressed spring and the bell crank lever will simultaneously be restored to its normal operative position shown in Figures 2 and 3.

The roll is completed, in the customary manner, by the application thereto of a band of felt 39 which may conveniently be glued or otherwise suitably combined with an inner band 40 of leather which is in turn riveted to a thin steel strip 41. The opposed ends of the said strip are turned inwardly, as depicted in Figure 5, to provide lugs 42 which are formed with holes 43 corresponding in position with the spikes 11 and 12 and the holes or recesses 13 and 14. The strip abrasive cloth or paper is placed around the felt 39 and is held by the spikes.

Now, before the ends of the abrasive strip can be impaled upon the spikes 11 and 12, these ends must, of course, first be turned down over the ends of the felt 39 to oppose the aforementioned lugs 42. If, as sometimes happens, the abrasive strip is somewhat wider than the rim of the roll, it would, unless special provision were made, be difficult, if not impossible, satisfactorily to tuck the ends of the strip down between the side cover 6 and the cover plate 37 at the location concerned. With a view to facilitating the turning down of the ends of an abrasive strip, the side cover 6 and the cover plate 37 are cut away as indicated at 44 and 45 in Figures 3 and 4 respectively.

What I claim then is:

1. A roll of the kind herein referred to which includes, in combination, a part formed with a hub, a cover portion which is combined with the said hub at one side of the roll, a separate and removable cover plate secured to the said part

at the opposite side of the roll, another part which is hinged to the first mentioned part and is movable between the cover portion and the cover plate, the said two parts being formed with complementary rim portions which, upon the parts being brought together, provide a continuous circular rim adapted for the support of a band of material for use in the performance of a finishing operation, and releasable latch mechanism for locking the said two parts together in the closed position for use, said mechanism comprising a pair of opposed engageable latch members which are carried by the respective roll parts and formed with complementary angular teeth, one of said latch members being movably mounted upon the hubbed roll part for movement relatively to the opposed latch member fixed on the other part, and a latch actuating member which is carried by the hubbed part and is operable at one side of the roll for action upon the movable latch member to withdraw the same and thereby effect release of the hinged part of the roll.

2. A roll of the kind herein referred to which includes, in combination, a part formed with a hub, a cover portion which is combined with the said hub at one side of the roll, a separate and removable cover plate secured to the said part at the opposite side of the roll, another part which is hinged to the first mentioned part and is movable between the cover portion and the cover plate, the said two parts being formed with complementary rim portions which, upon the parts being brought together, provide a continuous circular rim adapted for the support of a band of material for use in the performance of a finishing operation, and releasable latch mechanism for locking the said two parts together in the closed position for use, said mechanism comprising a pair of opposed engageable latch members which are carried by the respective roll parts and formed with complementary angular teeth, one of said latch members being mounted for movement slidably, under spring control, in a direction tangential with respect to the hub and relatively to the opposed latch member fixed on the other part, a latch actuating member which is carried by the hubbed part of the roll and is operable for action upon the movable latch member to withdraw the same and thereby effect release of the hinged part of the roll, and, for operating the latch actuating member, a push button arranged to work within an opening formed in the side cover plate.

3. A roll according to claim 2, wherein the slidable latch member is mounted for movement longitudinally within a bored lug extending laterally from the hub and is controlled by a compression spring interposed between its inner end and the opposed end of the bore which is closed.

4. A roll according to claim 2, wherein the operative end of the slidable latch member is formed with a single tooth adapted for co-operation with a toothed member which is fixed to the hinged part of the roll and is provided with circumferentially spaced catch teeth, for the purpose herein described.

5. A roll of the kind herein referred to which includes, in combination, a part formed with a hub, a cover portion which is combined with the said hub at one side of the roll, a separate and removable cover plate secured to the said part at the opposite side of the roll, another part which is hinged to the first mentioned part and is movable between the cover portion and the cover

plate, the said two parts being formed with complementary rim portions which, upon the parts being brought together, provide a continuous circular rim adapted for the support of a band of material for use in the performance of a finishing operation, and releasable latch mechanism for locking the said two parts together in the closed position for use, said mechanism comprising a pair of opposed engageable latch members which are carried by the respective roll parts and formed with complementary angular teeth, one of said latch members being mounted for movement slidably, under spring control, in a direction tangential with respect to the hub and relatively to the opposed latch member fixed on the other part, a bell crank lever which is fulcrumed on the hubbed part of the roll, a stud on one arm of said lever, said stud being located in a transverse recess formed in the slidable latch member and thereby adapted for action upon the slidable latch member, upon appropriate operation of the bell crank lever, to withdraw the said latch member and thereby effect release of the hinged part of the roll, and, for operating the bell crank lever, a push button which is attached to the other arm of the lever and is arranged to work within an opening formed in the side cover plate.

6. A scouring roll comprising, in combination, a part formed with a hub having a laterally extending bored lug, a cover portion which is combined with the said hub at one side of the roll, a separate and removable cover plate having an aperture formed therein and secured to the said part at the opposite side of the roll, another part which is hinged to the first mentioned part and is movable between the cover portion and the cover plate, the said two parts being formed with complementary rim portions which, upon the parts being brought together, provide a continuous circular rim adapted for the support of a band of abrasive material for use in scouring operations, a latch member which is mounted for longitudinal sliding movement within the aforesaid bored lug in a direction tangential with respect to the hub and is formed at its operative end with a single tooth, a compression spring interposed between the inner end of the slidable latch member and the opposed end of the bore which is closed, a further toothed member which is provided with circumferentially spaced catch teeth and is fixed to the hinged part of the roll, a bell crank lever which is fulcrumed on the hubbed part of the roll, a stud on one arm of said lever, said stud being located in a transverse recess formed in the slidable latch member and thereby adapted for action upon the slidable latch member, upon appropriate operation of the bell crank lever, to withdraw the said latch member and thereby effect release of the hinged part of the roll, and, for operating the bell crank lever, a push button which is attached to the other arm of the lever and is arranged to work within an opening formed in the side cover plate.

JOHN HUGH FRANKLIN.
